COMBINED CARRYING CASE AND PLAY SCENE FOR DOLLS

Derek J. Gay, Palos Verdes Peninsula, William H. Smedley, and Aaron G. Cohen, Los Angeles, and Michael W. Nuttall, South Pasadena, Calif., assignors to Mattel, Inc., Hawthorne, Calif.

Filed Nov. 15, 1973, Ser. No. 416,147

Term of patent 14 years

Int. Cl. D21—01

U.S. Cl. D34—15 A

FIG. 1

FIG. 2

FIG. 1 is a top perspective view of a combined carrying case and play scene for dolls showing our new design in a closed condition;

FIG. 2 is a bottom perspective view thereof;

FIG. 3 is a right side elevational view of the portable display toy in an open condition; and

FIG. 4 is a left side elevational view of the portable display toy in open condition.

We claim:

The ornamental design for a combined carrying case and play scene for dolls, as shown.
